TENT

Joseph A. Datz, Union, N. J.

Application April 4, 1939, Serial No. 265,902

5 Claims.

(Cl. 135—4)

The invention relates to tents and more particularly to a simple and rugged form of collapsible tent.

The tent is particularly adapted for use as a lawn tent, the side walls being made of netting provide for ample air circulation and being tightly closed prevent the entrance of insects. The top is preferably made of canvas and acts as a protection against the elements.

10 One of the objects is to provide a tent that may be easily and quickly erected or taken down by one person with a minimum amount of effort.

A further object is to provide a tent, which when collapsed takes up very little room.

15 Another object is to provide a tent which is very strong and rugged in construction and at the same time is of extremely light weight so that it may be easily carried from place to place.

20 Another object is to provide a tent in which no pegs or ropes are necessary either in erecting the tent or maintaining it in the erected position.

In addition to the foregoing other objects and advantages will become apparent as this specification proceeds. Referring to the drawings forming a part thereof, and in which a preferred embodiment of the invention is illustrated:

Fig. 1 is a perspective view, illustrating the tent in its erected position;

Fig. 2 is a perspective of the framework, the side walls and top being removed;

30 Fig. 3 is an elevational view showing the corner posts and rafter members in their collapsed or folded up position;

Fig. 4 is a fragmentary top plan view showing the center head, one rafter member being omitted and one shown as swung to its vertical position;

Fig. 5 is a side elevation of the parts shown in Fig. 4;

40 Fig. 6 is a sectional view on line 6—6 of Fig. 4;

Fig. 7 is a perspective view of the center head;

Fig. 8 is a fragmentary top plan view of the corner construction;

Fig. 9 is an elevational view of the corner construction, the side bar being omitted;

45 Fig. 10 is a fragmentary detail sectional view taken on line 10—10 of Fig. 8, the corner post being swung upward as it would appear in its folded position;

50 Figs. 11 and 12 are fragmentary detail sectional views taken respectively on the lines 11—11 and 12—12 of Fig. 9;

Fig. 13 is a side elevation of one of the corners;

55 Fig. 14 is a fragmentary elevational view looking at the inside of one of the corners;

Fig. 15 is a perspective view of one of the corner plates; and

Fig. 16 is a perspective view of one end of one 60 of the side bars and the brace attached thereto.

Referring again to said drawings the framework of the tent comprises corner posts 20, side bars 21, and rafter members 22, suitably connected together by pivoted and interlocking joints as illustrated in Fig. 2.

As shown in Fig. 1, the side walls 23 of the tent are made of netting and the top of canopy 24 is made of canvas, the side walls and top being suitably secured together. A zipper fastening 25 extends from the apex of the top and down the full length of one of the side walls, preferably at the central portion thereof. The fastener arrangement has two distinct advantages, one being that an absolutely tight closure is effected thus preventing the entrance of insects, and the other being that due to the closure extending over one half of the width of the tent the act of spreading the tent over the framework or removing it is greatly facilitated. The side walls being made of netting ample circulation of air is permitted and the entrance of insects prevented. The canvas top acts as a protection against the elements although the use of other materials for the top is not precluded. For instance, if one wanted a sun tent the top might also be made of netting.

The upper ends of the rafter members 22 are pivotally mounted for limited movement in a center head 30, see Figs. 4 to 7. This center head comprises a fixture having four sets of ears or lugs 31, each ear having an opening 32 for the reception of the pivot pin or rivets 33 for the rafter members. At the central portion of the center head or at what might be termed beyond the inner ends of the ears 31, the center head is cruciform in appearance and pockets are formed. Each of these pockets has a sloping bottom 34 against which the under faces of the upper extremities of the rafter members bear when they are in their operative position as shown in the right hand side of Fig. 6. The side walls of the pockets converge together as shown at 35 and the sides of the rafter member extremities are beveled off as indicated at 36 to cooperate with the converging side walls 35. The rafter members are thus positively positioned by what might be termed a wedging action when the framework is erected and a strong and rugged interlocking structure is provided.

When it is desired to collapse the framework, the rafter members 22 are turned down as indicated in Figs. 3 to 6. Their extremities are disengaged from their cooperating pockets and they rest in substantially parallel relation to each other.

Reference will now be had to the corner construction. The lower extremity of each of the rafter members is provided with a pivot pin 40. The pin 40 extends slightly beyond each side of the rafter member and engages openings 41 in

corner plates 42 as shown particularly in Figs. 11 and 12. The corner plates are L-shaped in formation and are secured to opposite sides of the corner posts 20 by rivets 44 passing through 5 suitable apertures 45 in the vertical legs of the corner plate. The openings 41 for the pivot pins 40 are formed in the horizontal legs of the corner plates. It will be noted the lower extremities of the rafter members extend beyond the 10 corner posts and the tops of the corner posts are angularly slabbed off to engage the under sides of the rafter members as shown at 46 in Figs. 3, 9 and 10. Thus a strong, simple and accurate positioning means is provided for the corner 15 posts and rafter members.

When it is desired to collapse the framework, the corner posts are swung on their pivots almost 270° until they are in substantially parallel relation with the rafter members as indicated in 20 Figs. 3 and 10.

The means for interlocking the framework in its assembled and erected position comprises the 25 insertion of the side bars 21. For this purpose the side plates have laterally extending pockets 47 having top and bottom walls 48 and end walls 49. Both ends of each of the side bars 50 are formed with a double bevel as indicated at 51 in Figs. 8, 11 and 16. One of the bevels or sloped faces on each end rests against the face of the 30 corner plate and the other bevel or sloped face rests against the end wall 49 of the pocket on the corner plates. The side bars are made a trifle longer than the actual distance from pocket to pocket on each corner post. In the 35 erected position they are thus under a slight compression and function most effectively to maintain the framework in its assembled position.

The corner posts 20, side bars 21 and rafter 40 members 22 are preferably made of wood or some other light and strong material and the center head and corner pieces are made of an aluminum alloy which combines strength and lightness.

As an additional strengthening means corner 45 braces 55 are provided. Their upper ends are pivoted at 56 to the side bars and the lower ends have open slots 57 which are hooked over a stud 58 on the corner posts and secured in place by a wing nut 59, see Figs. 13, 14 and 16.

Changes in details of construction and 50 arrangements of parts may be made by one skilled in the art and such changes are to be considered as coming within the spirit of the invention as set forth in the appended claims.

55 I claim:

1. A collapsible framework for a tent, said framework having in combination corner posts, corner plates secured to either side of said corner posts, rafter members pivoted between each pair 60 of corner plates, a center head in which said rafter members are pivoted, and side bars extending between said corner plates, the length of said side bars being slightly more than the distance between said corner plates so that they are under a slight compression when in position and effectively function to maintain the entire framework in its assembled or erected position.

2. A collapsible framework for a tent, said framework having in combination corner posts, corner plates secured to either side of said corner posts, rafter members pivoted between each pair 65 of corner plates, a center head in which said

rafter members are pivoted, pockets formed in said center head for the reception of said rafter members, said pockets having a sloping lower wall and converging end walls, the lower surfaces of the ends of said rafter members engaging the 5 sloping lower walls of said pockets and the ends of said rafter members being beveled to cooperate with the converging end walls of said pockets, and side bars extending between said corner plates, the length of said side bars being slightly 10 more than the distance between said corner plates so that they are under a slight compression when in position and effectively function to maintain the entire framework in its assembled or erected position.

3. A collapsible frame work for a tent, said framework having in combination, corner posts, corner plates secured to either side of said corner posts, pockets formed on the exposed surfaces of 15 said corner plates, rafter members pivoted between each pair of corner plates, a center head in which said rafter members are pivoted, and side bars extending between and having their ends positioned in the pockets of said corner plates, the length of said side bars being slightly 20 more than the distance between said pockets so that they are under a slight compression when in position and effectively function to maintain the entire framework in its assembled or erected position.

4. A collapsible frame work for a tent, said framework having in combination, corner posts, the upper ends of said corner posts being angularly beveled, corner plates secured to either side 25 of said corner posts, pockets formed on the exposed surfaces of said corner plates, rafter members pivoted between each pair of corner plates, the under surfaces of said rafter members engaging the beveled upper ends of said corner posts, a center head in which said rafter members are pivoted, and side bars extending between and having their ends positioned in the pockets of said corner plates, the length of said side 30 bars being slightly more than the distance between said pockets so that they are under a 35 slight compression when in position and effectively function to maintain the entire framework in its assembled or erected position.

5. A collapsible frame work for a tent, said framework having in combination, corner posts, corner plates secured to either side of said corner posts, pockets formed on the exposed surfaces of said corner plates, rafter members pivoted 40 between each pair of corner plates, a center head in which said rafter members are pivoted, 45 pockets formed in said center head for the reception of said rafter members, said pockets having a sloping lower wall and converging end walls, the lower surfaces of the ends of said rafter members engaging the sloping lower walls 50 of said pockets and the ends of said rafter members being beveled to cooperate with the converging end walls of said pockets; and side bars extending between and having their ends positioned in the pockets of said corner plates, the length 55 of said side bars being slightly more than the distance between said pockets so that they are under a slight compression when in position and effectively function to maintain the entire framework in its assembled or erected position.

70 JOSEPH A. DATZ.
